UNITED STATES PATENT OFFICE

170,341

RING OR THE LIKE

Evaline L. Schenck, Columbus, Ohio

Application November 20, 1951, Serial No. 17,480

Term of patent 14 years

(Cl. D45—10)

To all whom it may concern:

Be it known that I, Evaline L. Schenck, a citizen of the United States of America, residing at Columbus, in the county of Franklin, State of Ohio, have invented a new, original, and ornamental Design for a Ring or the like, of which the following is a specification, reference being had to the accompanying drawing, forming part thereof.

Fig. 1 is a top plan view of a ring disclosing my new design, and

Fig. 2 is a side elevation thereof.

The dominant feature of the design is disclosed in full lines.

I claim:

The ornamental design for a ring or the like, substantially as shown and described.

EVALINE L. SCHENCK.
